UNITED STATES PATENT OFFICE.

JOSEPH M. VIETTI, OF CLINTON, INDIANA.

SWIMMING POOL.

Application filed August 1, 1927. Serial No. 209,896.

The present invention relates to bathing beaches and has for its primary object to insure sanitation in connection with the swimming and bathing pools. Other objects are 5 the prevention of persons entering the beach inclosure who are not provided with the regulation bathing equipment. Other objects and advantages of the invention will appear from the following specification and claims.

10 In the drawings:

Figure 1 is a plan view showing the relation of parts by way of illustration of the invention.

15 Figure 2 is a section through the inclosure on the line 2—2 of Figure 1.

Figure 3 is a detailed view on the line 3—3 of Figure 1, showing the relation of showers to one of the wading pools and to the baby pool.

20 Figure 4 is a detail on the line 4—4 of Figure 1, showing the relation of one of the wading pools to the dressing rooms and to the baby pool.

25 Figure 5 is a detailed view showing the relationship of one of the cuspidors to the cement rest platform.

Referring to the drawings in detail, 10 designates an inclosure having gates at 11 through which patrons may enter and pass 30 to one of the check rooms 12 through the gateways 13 and 14. Lying between the check rooms, or in any other suitable relation thereto found desirable, is the swimming pool 15 separated from the check rooms by wading 35 pools 16. Also lying between the check rooms and at one end of the swimming pool 15 is the baby pool 17 separated from the swimming pool by a wall and of a depth suitable for children. The inclosures 18 surrounding the wading pool are provided with passageways 19 and 20, the first of which leads to a promenade 21 and the second to the baby pool. The 40 passages from the check rooms, both to the baby pool and to the promenade, are guarded by sprays or showers 22 so that a person desiring to enter the swimming pool or the baby pool will not only be obliged to pass through one of the wading pools but also through a shower. Silica sandbars may be arranged at 45 31^a at the sides of the baby pool. At the rear of the baby pool and substantially along the whole space between the wading pools is provided an apertured pipe 23 providing sprays which feed the baby pool and through spillways 24 also feed the swimming pool. Steps 50 25 may be provided leading from the baby

pool to the swimming pool and rest platforms, such as shown at 26 and 27, may be located at desirable points in the swimming pool. For purposes of further insuring sanitation, 60 cuspidor recesses such as shown at 28 may be provided in these rest platforms, around the inside edge of the pool proper and also around the outside edge, which are connected through suitable pipes 29 with a sewer or the like, not 65 shown. These cuspidors are preferably fed with a spray from apertured pipes 30. A sink such as is illustrated at 31 may be provided and suitable pumps, not illustrated, may be used to keep the water in constant circulation 70 through the pool, sink and back through the spray pipe 23.

By the above described arrangement it will be readily seen that no one can enter the inclosure of the swimming pool or baby pool 75 without passing through the wading pool and showers, thus insuring cleanliness of the persons entering the inclosure. At the same time the circulation of the water through the showers thoroughly aerates the same and subjects it in a fine spray to the sunlight, in this manner tending to oxidize all impurities and purifying the water used in the pools, and for heating the water by natural sunlight.

It is to be understood that the construction 80 of such pools as hereinabove described is preferably of concrete, although the material used may be varied without departing from the spirit of the invention.

Having described my invention what I 90 claim is:

1. In a device of the character described, a swimming pool, check rooms adjacent said pool, wading pools between said check rooms and swimming pool, and showers guarding 95 all passages from the wading pools to the swimming pool.

2. In a device of the character described, a swimming pool, check rooms spaced from said swimming pool, passageways leading from 100 said check rooms to said pool, said passageways being guarded by showers and wading pools.

3. In a device of the character described, a swimming pool, check rooms spaced from said 105 swimming pool, passageways leading from said check rooms to said pool, said passageways being guarded by showers and wading pools, and an inclosure preventing access to said pool except through the check rooms.

4. In a bathing beach, a swimming pool, check rooms and passageways between the

check rooms and swimming pool, a spray feeding water to said pool, and wading pools between the check rooms and the pool.

5. In a bathing beach, an inclosure there-
for, check rooms and a swimming pool separated by wading pools, a spray device feed-
ing to said pool, wading pools, sprays guard-
ing the passage through the wading pool, a
baby pool receiving the spray from said
spraying device, and said baby pool having
spillways emptying into the swimming pool.
6. In a bathing beach, a check room forming

the only access to the pool, a wading pool, a shower thereat, a swimming pool adjacent of the shower, a shallow children's pool and 15 a bank of silica therein.

7. In a bathing beach, a check room giving access to the swimming pool and children's pool, showers at bath, a wading pool leading to both and a rest platform in the swimming 20 pool with sanitary connections with a drain.

In testimony whereof I affix my signature.

JOSEPH M. VIETTI.
